Primary Examiner — Catherine R Oliver-Garcia

(57) **CLAIM**

The ornamental design for a wrist rearview mirror, as shown and described.

DESCRIPTION

FIG. 1 is a front and top perspective view of the wrist rearview mirror showing my new design;

FIG. 2 is rear and bottom perspective view thereof;

FIG. 3 is a front elevational view thereof;

FIG. 4 is a rear elevational view thereof;

FIG. 5 is a left side elevational view thereof, the right side elevational view being a mirror image of FIG. 5;

FIG. 6 is a top plan view thereof;

FIG. 7 is a bottom plan view thereof;

FIG. 8 is a perspective view thereof, when the upper cover of a wrist rearview mirror is opened;

FIG. 9 is a perspective view thereof, showing the state of use when a wrist rearview mirror is attached to the wristband; and,

FIG. 10 is another perspective view thereof, showing the state of use.

The broken lines depict environment that forms no part of the claimed design.

1 Claim, 10 Drawing Sheets
